STORAGE PILE MATERIAL HANDLING APPARATUS

Joseph E. Dunasky, Cleveland, Ohio

Application April 21, 1945, Serial No. 589,621

15 Claims. (Cl. 214—10)

1

This invention relates to improvements in material handling apparatus and, more particularly, to equipment for reclaiming i. e., recovering, granular bulk material, such as ore, coal, and the like from stock or storage piles or bins.

Where bulk material is stored on the ground in piles exposed to the weather and recovered from such piles by dragline or overhead bucket systems, the operations are slowed and reserve man-power must be maintained during the times that the storage piles are usually most heavily drawn upon, namely, during freezing weather, when the removal of frozen material takes on the aspects of a quarrying operation. When such open pile systems are used for bedding and blending operations, a further difficulty is presented in recovering vertically extending sections of the pile (which is built up from horizontally extending layers of different analyses) so that the average analysis of recovered stock is substantially constant. Such bedding and blending operations are becoming of increasing importance as a means for effecting better production control. At the present time, the most successful equipment for reclaiming stock in such bedding operations employs at least one large scraper which is laid against a vertically sloping transverse face of the pile; the scraper is reciprocated to scrape material off the face of the pile, the scraped material falling to the base of the pile, whence it is conveyed by plow and belt conveyer systems to a central recovery point. A major objection to such equipment is that both the large initial cost and the operating and maintenance costs materially affect the cost of the bedding operation. Bin systems, in which material is reclaimed through manually operated or controlled gates in the bottom of the bins, are sometimes employed where it is necessary to prevent the deleterious effects of exposure to weather, but such storage bin systems are often objectionable because of the difficulty in operating the gates and because such bins often enhance segregation between large and fine particles in the stored material. Bin systems having anywhere near the usual capacity of open storage piles would also usually be prohibitively expensive for materials such as iron ore, coal, gravel, and the like.

It is the object of my invention to provide reclaiming apparatus which is relatively inexpensive and yet substantially fully automatic in operation, requiring a minimum of operating, supervising, and maintenance personnel. It is a further object of my invention to provide apparatus for continuously reclaiming material from

5 a vertically sloping face of the body of stored material, thus making my equipment particularly advantageous for bedding and blending operations. My apparatus may be used either in connection with open storage piles or bins having a continuous bottom; when used in connection with storage piles, the operation is not seriously effected by freezing weather, when used in connection with a continuous bottom bin, the difficulty with gate operation is eliminated and the effect of segregation is reduced, if not eliminated. More specifically, it is the object of my invention to provide a continuous gate system automatically opened and closed by and in combination with a belt conveyer loader; this apparatus may be incorporated in an underground conveyer gallery beneath a storage pile or attached to the bottom of a storage bin.

10 Other objects and advantages of this invention will be apparent from the following specification, claims, and drawings, in which:

Fig. 1 is a vertical section through an open storage pile and associated conveyer gallery employing my apparatus.

15 Fig. 2 is an enlarged front elevation, partly in section, of my apparatus as shown in Fig. 1.

Fig. 3 is an enlarged detail section taken along the line 3—3 of Fig. 10.

20 Fig. 4 is a longitudinal section taken along the line 4—4 of Fig. 2.

Fig. 5 is a top plan view of the hopper car shown in Fig. 4.

25 Fig. 6 is a top plan detail of the continuous gate shown in section in Fig. 4.

Fig. 7 is an enlarged detail, partly broken away, of a gate locking lug and hinge shown in Fig. 6.

30 Fig. 8 is a longitudinal vertical section taken along the line 8—8 of Fig. 7.

Fig. 9 is a transverse vertical section taken along the line 9—9 of Fig. 7.

35 Fig. 10 is a detail elevation of the hopper car showing the position of the elements thereof, in relation to the gate structure, during return travel of the car.

40 In the illustrative embodiment of my invention shown in the drawings, the long bedding and blending stock pile 10 (shown only in transverse section in Fig. 1) is built up of several successive horizontal layers of material 10a, 10b, et cetera, and is held above the underground tunnel 11 by means of the graded embankments 12 and 13. The parallel embankments 12 and 13 are conveniently formed when excavating for the tunnel 11, though obviously any other convenient parallel 45 side supports for the pile 10 may be employed.

The stock pile 10 may be built up by any suitable overhead tripper conveyor system (not shown) which will dump material between the embankments; the stock pile so formed usually extends for the length of the tunnel 11. In actual stock yard practise, several parallel piles are usually employed, the overhead tripper conveyor running between the parallel piles and the conveyor belts in the several tunnels loading onto a collector belt adjacent the discharge ends of the tunnels. For the purposes of this invention, however, only one stock pile 10 need be shown.

The concrete tunnel 11 provides a conveyor belt gallery, on the floor of which the conveyor belt 15 is supported on conventional trough rolls 16 and return rolls 17. The conveyor belt 15 is driven by any suitable means (not shown). The conveyor belt 15 carries material discharged upon it to any suitable transfer hopper, collector belt, or the like (not shown). Suitably supported on the floor of the tunnel 11 on either side of the conveyor belt 15 are the rails 18 upon which the hopper car 20 runs.

Hopper car, drive, and operation

The hopper car 20, as shown in Figs. 2, 4, and 5, is comprised of a main frame 21 supported on the rear wheels 22 and front drive wheels 23, which run on the rails 18. In the embodiment shown, the rear portion of the hopper car 20 carries the hopper 25, which is comprised of an upper four-sided hopper box 26 open at the top and bottom. Below the hopper box, converging side wear plates 27 and front plate 28 direct material falling through the hopper box onto the bottom pusher plate 30 mounted for longitudinal reciprocating movement on the transverse rollers 29 carried below the hopper 25. The rear of the hopper 25 below the hopper box is open, the sides of the hopper adjacent the pusher plate 30 extending rearwardly to provide tail plates 31 for directing material discharged from the end of the pusher plate and the rear of the hopper onto the center of the conveyor belt 15.

The drive for the particular hopper car shown comprises an upper power take-off sheave 32 mounted close enough to the forward end of the hopper car 20 that the upper lay of the belt 15, when lifted from the troughing rolls 16 to pass over the sheave 32, will clear the front end of the hopper car. Located forwardly of the upper sheave 32 is the lower power take-off sheave 33, the conveyor belt 15 passing first around the upper sheave 32 and then around the lower sheave 33, sufficient wrap being obtained to drive both. From the lower sheave 33 the belt 15 drops down onto the troughing rolls 16 which support the belt as it receives material discharged from the hopper 25, as shown in Fig. 4.

The upper sheave 32 is provided with outboard cranks 35 which, through the pivoted yokes 36 and connecting rods 37, pivotally connected to the ends of the yokes 36 and the forward end of the pusher plate 30, reciprocate the pusher plate 30 to discharge material from the rear of the hopper 25. The lower sheave 33 is provided with an outboard sprocket 38 which, through the chain 39, drives the input shaft 40 of the two-stage gear reducer 40. The first-stage, or high-speed reversing, output shaft 41 of the reducer 40 drives the front car drive wheels 23 through the clutch 42 and sprocket drive 43. The second-stage, or low-speed forward, output shaft 44 of the reducer 40 drives the front car drive wheels 23 through the clutch 45 and sprocket drive 46.

The two clutches 42 and 45 are interconnected by the clutch yoke 47 so that only one or the other may be engaged, the clutches also being spaced so that, when the yoke 47 is in its central position, as shown in Fig. 5, neither clutch is engaged and the car drive is in neutral. Suitable brakes (not shown) may be engaged when the yoke 47 is held in its neutral position to hold the hopper car 20 if the clutches are disengaged during the course of the run of the car 20 through the tunnel 11.

From the foregoing it should be apparent that, with the clutch 45 engaged, the hopper car 20 will be driven forwardly through the tunnel 11 as the conveyor belt moves rearwardly carrying material discharged from the hopper 25; the forward movement of the car 20 being slow relative to the rearward speed of the conveyor belt due to the reduction effected by the reducer 40. At the forward end of the travel, the yoke 47 is shifted, either manually or by a suitable shifting cam (not shown) mounted on the side of the tunnel 11. With the clutch 42 engaged, a relatively quick return of the hopper car to the rear end of the tunnel is obtained, where the yoke 47 is again shifted to obtain forward travel, thus completing the cycle of reciprocating travel of the hopper car through the length of the tunnel 11. Obviously, the forward or belt-loading travel of the car contra to the movement of the belt 15 is a mere matter of choice, the only requirement being that the belt convey discharged material away from the hopper car. Thus, if the rotational directions of the output shafts 41 and 44 were reversed, the rear end of the hopper car would become the forward end and, in so far as the belt-loading would be concerned, the hopper car would operate just as well, though the belt and car would be moving in the same direction. The drive of the hopper car by means of a power take-off from the conveyor belt is preferred because of its safety, simplicity, and predetermined ratio between belt speed and car travel. Obviously, within the scope of this invention, variable speed devices may be incorporated, if desired, or the car and hopper discharge may be driven by other suitable means, as, for example, by electric motors receiving their power from trolleys or third rails. Where means other than a flexible conveyor belt, such as plow conveyers, chutes, etc. are employed to convey material away from the hopper car or its equivalent, a motor drive may be preferred or even required.

Continuous gate structure and operation thereof

Serving as a ceiling for the tunnel 11 and a floor for the stock pile 10 throughout its length is the continuous gate structure 50 supported by the longitudinally extending cantilever beams 14 of the tunnel 11. The continuous gate structure 50 is comprised of a pair of parallel T-section side members 51 anchored to the beams 14, said side members 51 carrying, at adjacent edges of their horizontal webs, channels 52 in which are journaled at equal spaced intervals the transversely extending gate pins 53 carrying the gate plates 54. When held in their normal horizontal position, as shown in Figs. 2, 4, and 10, for example, the gate plates close the gate space between the side members 51; when unsupported, the gate plates 54 fall rearwardly (since they are supported at their rear edge by the pins 53) to open the gate space between the side members 51, as shown in the portion of the gate

structure above the hopper 25 in Fig. 4. Thus, material normally supported above the gate plates 54 will fall through the gate space and into the hopper 25 (since the gate plate opening and closing is controlled by the movement of the hopper car 20, as explained below).

As best shown in Figs. 6 to 9, the gate plates 54 are held in their normally closed position by the pivotally mounted locking lugs 55. The locking lugs 55 are carried in pairs, each lug being oppositely mounted in a side member 51 on a shouldered pivot bolt 56 and hanger strap 57. The hanger strap is supported by the pivot bolt 56 and hanger bolt 58; the shoulder on the pivot bolt 56 and the washer 59, carried by the bolt 58, prevent the bolts 56 and 58 from being tightened until the lug 55 is jammed between the hanger strap 57 and the horizontal web of the side member 51. In addition to supporting the lug 55, the hanger strap 57 extends between the forwardly divergent depending releasing cam face 60 and locking cam face 61 of the lug 55 to limit the pivotal movement of the lug 55. Thus, as shown in Figs. 4 and 6, when the lugs 55 are swung toward each other to project beyond the inner edges of the side members 51 and engage the under-surface of a corresponding gate plate 54, the gate plates are held in their normally closed position; when the lugs 55 are swung apart, the gate plates 54 drop and the continuous gate is opened above the hopper 25, the gate plates falling into the upper opening in the hopper box 26. To minimize friction as the gate is opened and closed, the upper and lower surfaces of the lugs 55, the lower surfaces of the plates 54, and the upper surface of the strap 57 are preferably finished and lubricated, although, as explained below, the load on the lugs 55 is at least partially, if not completely, relieved as the gate is opened and closed.

The means for opening and closing the gate plates 54 (so that the continuous gate structure 50 is automatically opened only over the hopper box 26) is a gate operating assembly 75, carried in the upper portion of the hopper box 26. The assembly is comprised of a frame 62 journaled for vertical movement in the antifriction rollers 63 carried by the upper portion of the hopper box 26. (See Fig. 3.) Parallel sides of the frame 62 rest on rollers 64 mounted on pins 65, each pin 65 extending through a suitable arcuate slot 66 in the hopper box 26. Each pin 65 is supported in the arms of a pivotally mounted fork 67. Journaled in the frame 62 and extending slightly above it are a pair of transverse gate plate rolls, a forward roller 68 and a rear roller 69, the bearing surfaces of the rollers 68 and 69 being located so that they will engage the plates 54 inwardly of the locking lugs 55. Mounted on the frame 62 slightly forwardly and outwardly of the bearing surfaces of the roller 68 are a pair of lug-releasing cams 70 having inwardly converging forward surfaces. Mounted slightly rearwardly of the roller 69 are a pair of lug-locking cams 71 having slightly outwardly diverging forward surfaces.

The minimum lateral space between the face of a releasing cam 70 and the face of its corresponding locking cam 71 is slightly greater than the minimum distance between the cam faces 60 and 61 of a lug 55, the cams 70 and 71 being spaced on the frame 62 so that, as the rollers bear against the plates 54 and as the hopper car 20 moves forwardly in the tunnel 11, the cams 70 will first engage the releasing cam faces 60 of

a pair of locking lugs 55 to move the lugs outwardly to their releasing position; the corresponding plate 54 thus drops to its open vertical position. Then, as the car 20 continues to move forward, the opened, vertically hanging plate 54 will be engaged by the rear plate roller 69, lifted to its horizontal position and, while so lifted, the locking cams 71 will engage the locking cam faces 61 of the corresponding lugs 55 to swing the lugs 55 inwardly, thus locking the plate 54 in its normal closed position.

Thus it will be seen from the foregoing that, as the hopper car is driven forwardly in the tunnel 11, the gate operating assembly 75, comprised essentially of the frame 62 carrying the rollers 68 and 69 and the cams 70 and 71, does, in effect, automatically "zipper" the continuous gate 50 open and closed as the hopper 25 passes under the gate.

To insure that the rollers 68 and 69 will engage the plates 54 and, also, to allow for unevenness in the plates and the joints between them, the pairs of the forks 67 on each side of the hopper box 26 are tied together through the fork shaft 25. Thus, all forks 67 move in unison. During forward movement the forks are pivoted so that the pins 65 are in the forward portions of the arcuate slots 66 below the crowns thereof, the maximum vertical distance between the crowns of the slots 66 and the under-surface of the plates 54 and the vertical height of the gate operating assembly 75 being such that the rollers 68 and 69 will engage the under-surface of the plates 54 before the forks 67 can be pivoted rearwardly past their vertical position. The forward forks 67 are provided with bell-crank extensions 78 which engage the pin 79 of the compression spring assemblies 80, which assemblies 80 tend to urge the forks 67 rearwardly of their vertical position. Thus, during forward travel of the hopper car, the rollers 68 and 69 are held against the plates 54 by the resilient influence of the compression spring assemblies 80. Further, to the extent that the load of the material on the plates 54 is carried by the resilient vertical pressure of the rollers 68, the frictional load on the lugs 55 is relieved as the plates 54 are released for opening the continuous gate 50.

To permit the return movement of the hopper car, the car travels forward under the apron 81 beyond the forward end of the gate 50. The under surface of the apron is relieved to permit rollers 68 and 69 to be raised above the level of the gate 50 and, thus, to permit the forks 67 to be moved rearwardly of their vertical position. As the roller 69 clears the edge of the apron 81, the shifting bar 76 strikes the block 82, which action, plus the influence of spring assemblies 80, first raises and then drops the assembly 75 as the pins 65 move rearwardly in the slots 66. The rearward ends of the slots 66 are well below their crowns, so that, as shown in Fig. 10, the rollers 68 and 69 and cams 70 and 71 are safely clear of the plates 54 and lugs 55 when the hopper car is returned to its starting position. To raise the assembly 75 to its gate operating position, a shifting lever actuating block 83, similar to the block 82, is provided at the other end of the tunnel.

Summary

It should be apparent from the foregoing that this invention provides a substantially fully automatic means for reclaiming stored materials, requiring, in general, only supervisory personnel to start and stop the reclaiming operations.

Maintenance requirements are, in general, minimized; the gate plates employed in the disclosed preferred embodiment are self-clearing, as will be apparent from Fig. 4; thus, there is little possibility for jamming the gate plates 54 during opening and closing; substantially all other operating parts are protected from weather and the material.

In using the embodiment disclosed for blending materials, it is the usual practise to reclaim an entire stock pile built up of horizontal layers or beds of the materials to be blended and then to build up a new pile only after a reclaimed pile has been entirely removed. This type of practise means that the operation of the conveyer belt, and, consequently, the gate-opening hopper car, is stopped before the hopper car starts to repeat a reclaiming trip for the period of time required to rebuild another pile. In this connection, it should be noted that this apparatus blends the materials in horizontal beds in the pile because, when a gate opens, it, in effect, removes an upwardly slanting slice of the horizontal layers in the pile; if each layer 10a, 10b, et cetera, is equal in thickness throughout the length of the pile, then, of course, the average composition of the successive slices removed by the opening of successive gates will be substantially constant. Of course, if the apparatus is used merely for reclaiming without regard to blending, or if blending is accomplished by building up a repeated pattern of layers sloping at an angle contra to the angle of the slices removed by the successive operation of the gate plates (such blending practise is better adapted to blending bins drawing from a variety of stock piles of known composition, rather than for storage piles), then, of course, it is possible to operate the apparatus without interruption (other than for quick returns of the hopper car) by building up a new pile on a cleared portion of the gate 50 while the hopper is reclaiming material from an old pile. In fact, if such continuous operation of the hopper car is contemplated, it is possible to adopt the gate to a circular or circuit form, rather than the straight-line form disclosed.

It is also to be noted that as each gate plate 54 is opened, material supported thereon will tend to surge into the hopper car. To accommodate such surging, the length of the hopper box and the longitudinal distance between the rollers and cams of the gate operating assembly 75 are purposely designed so that an immediately preceding gate plate will be open for a period of time after its succeeding gate plate is open, as shown in Fig. 4. Thus, material which might spill over the opening of a recently opened gate plate will usually fall through the opening of the immediately preceding and still unclosed gate. The capacity of the hopper 25 is, of course, designed to accommodate such surges of material so that material will be fed onto the conveyer belt at a substantially constant rate. Because material is reclaimed from the bottom of the pile, the difficulties heretofore encountered with open piles during freezing weather are largely overcome. When material is withdrawn, any unsupported frozen crust of material will usually break up of its own weight as it drops onto the foot of the pile; if the crust becomes so thick that it tends to form a complete arch over the gate, such an unsupported arch may be broken with relative ease.

It should be apparent that the above disclosed generally preferred embodiment may be altered

or modified, either in whole or in part, to accommodate my invention to specific uses or situations. Thus, for example, it is readily apparent that my continuous gate structure 50 and operating assembly 75 may be attached to the bottom of a storage bin. Further, while my transversely pivoted gate plates 54 are generally preferred because of their simplicity, their inherent strength which requires no bracing which would interfere with the flow of material, their self-clearing operation, and other desirable characteristics, other types of gates may, within the broad scope of this invention, be employed; for example, longitudinally pivoted gate plates or sliding gate plates (with the necessary modification of the camming action of the operating assembly 75) may be employed. It is apparent, therefore, that the scope of this invention is not limited to the illustrative preferred embodiment disclosed but by the appended claims.

What is claimed is:

1. In material handling apparatus of the class described, a longitudinally extending trough-shaped means, a continuous gate structure at the bottom of said trough means, said gate structure comprising spaced support members extending along the bottom of said trough means, a plurality of adjacent gate members normally closing the space between said supporting members to serve as a floor for said trough means, said gate members being movable to an open position, whereby material in said trough will flow between said spaced support members, and means associated with each of said gate members for locking each of said gate members in its closed position independently of adjacent gate members, means movable beneath said gate structure to act on said locking means to release said gate members, means to drive said gate lock actuating means beneath said gate structure to successively unlock said gate members and open integers of the gate opening, means to convey away material falling through the successively opened integers of the gate opening, and gate closing means operatively connected with said gate unlocking means and following said gate unlocking means to move said gate members to their normally closed position and relock said gates in their closed position.
2. In material handling apparatus of the class described, troughing means, a conveyer gallery below said troughing means, a continuous gate structure serving as a floor for said troughing means and as a ceiling for said gallery, said gate structure being comprised of a plurality of adjacent gate members movable from a normally closed position to an open position, a conveyer movable through said gallery, and gate operating means to open said gate members in succession, and means to drive said conveyer and operate said gate operating means in timed relationship to the movement of said conveyer.
3. In material handling apparatus of the class described, a conveyer gallery, a continuous gate structure for supporting granular material thereon and serving as a ceiling for said conveyer gallery, said gate structure comprising parallel spaced supporting members, a plurality of adjacent gate members pivotally mounted to close the space between said support members and movable under the influence of material supported thereon to a position opening the space between said support members, and means to lock said gates in their closed position, a conveyer

movable through said gallery beneath said gate structure, and means operating in timed relationship to the movement of said conveyor to open said gate members in succession and allow material to flow through the opened space between said support members, means to direct material flowing through said gate structure to said conveyor, and means to close and relock said gate members after said gate members have been opened.

4. In material handling apparatus of the class described, a conveyer gallery, a continuous gate structure for supporting granular material thereon and serving as a ceiling for said conveyer gallery, said continuous gate structure comprising parallel support members, a plurality of adjacent gate members pivotally mounted to open and close the space between said support members, said gate members being movable from a closed to open position by the weight of material supported thereon, and means associated with each of said gate members for locking said gate members in their closed position, a conveyer movable in said gallery, a hopper car movable in said gallery beneath said gate structure and above said conveyer to direct material flowing through said gate to said conveyer, means for driving said hopper car in timed relationship to the movement of said conveyer to permit said conveyer to convey material away from said hopper, means carried by said hopper car to act successively on said locking means and unlock said gate members in succession as said hopper car moves through said gallery, means to close said gate members, and means carried by said hopper car to act on said locking means to lock said gate members in a closed position after said gate members have been opened.

5. Material handling apparatus as defined in claim 4 including means carried by said hopper car to relieve the load on said gate members while said gate members are being unlocked.

6. In apparatus for handling material of the class described, a conveyer gallery, a belt conveyor driven through said gallery, a car movable through said gallery, a hopper carried by said car and located above said belt, means actuated by said belt to drive said car in a direction and at a speed to remove material deposited on said belt by said hopper away from said car, a continuous gate structure serving as a ceiling for said gallery and as a floor on which material to be reclaimed may be deposited, said continuous gate structure comprising spaced supporting members defining a gate space therebetween, said gate space extending above and parallel to said belt, adjacent gate plates, each pivotally mounted in said supporting members for movement from a horizontal position to a vertical position in which the center of gravity is below the point of pivotal support in said supporting members, adjacent edges of said gate plates substantially touching when said gate plates are in their horizontal position closing the gate space, and pivotally mounted lugs for locking the gate plates in their horizontal closed position, a first cam means carried by said hopper car for acting on said lugs to allow said gate plates to fall to a vertical position above said hopper, means carried by said hopper car for raising said gate plates to a closed position, and a second cam means carried by said car for acting on said lugs to lock said gate plates in a closed position, said first and second cam means and said gate closing means being located on said car with respect to the direction of travel of said

car to first open and then close said gate plates in succession and above said hopper as said car is driven through said gallery.

7. In apparatus as defined in claim 6, in which 5 said gate closing means, said first and second cam means, and means for exerting upward pressure on the undersurface of gate plates comprising a gate operating assembly carried by said hopper car, and including means to disengage said gate operating assembly from said gate structure.

8. In apparatus of the class described, gate operating means for a continuous gate comprising a plurality of successive gate members each 15 locked by pivotally mounted locking lugs, said gate operating means comprising a car driven beneath the continuous gate, a first cam means engaging the locking lugs of a gate member to unlock said member, means to move a gate member to a closed position, and a second cam means to engage the locking lugs to lock the gate member in a closed position, said cam means being carried by said car, and means to drive said car, whereby successive gate members will be unlocked and then locked as said car is driven beneath the gate structure.

9. In apparatus of the class described, gate operating means for a continuous gate structure comprised of successive pivotally mounted gate 30 plates each normally locked in a closed position, said gate operating means comprising a car driven under said continuous gate structure, a hopper on said car, a gate operating assembly mounted on said hopper and comprising a first cam means for releasing the gate locking means, means for 35 swinging a gate plate to its closed position, and a second cam means adjacent said gate closing means to actuate the gate-locking means and lock said gates in a closed position, whereby said gate structure will be opened at integers above said hopper.

10. Apparatus as defined in claim 9, including 40 a plate supporting roller located adjacent said first cam means, and means to urge said roller into engagement with gate plates thereabove, whereby the load on the first cam means will be relieved by the effect of the pressure exerted by the plate supporting roller upon the gate plates to be unlocked by the first cam means.

50 11. Apparatus as defined in claim 9, including means to withdraw the gate operating assembly from engagement with the gate structure.

12. In an apparatus for handling material of the class described, a continuous gate structure 55 comprising means defining a longitudinally extending gate opening, a plurality of removable gate plates continuously biased toward an open position but normally held in a position to close said gate opening, means associated with each 60 of said gate plates for releasably holding its associated plate in a closed position, the closing means for each gate plate being independent of the closing means for the other gate plates and means to actuate said gate plate holding means successively to release said gate plates, whereby 65 successive actuation of said gate plate holding means to release their associated plates will open successive integers of said gate opening.

13. In apparatus for handling material of the 70 class described, a continuous gate structure comprising supporting means defining a longitudinally extending gate opening, spaced pivots carried by said supporting means, said pivots having axes extending transversely of said gate opening, a gate plate mounted adjacent a transverse edge

on each of said pivots, whereby each of said plates is continuously biased toward a vertical position, the width of said gate plate being substantially equal to the width of said gate opening and the length being substantially equal to the longitudinal spacing between said pivots, whereby each of said plates will close an integer of said gate opening when said plate is in a horizontal position, means associated with each of said plates to lock the associated plate in a horizontal position, said locking means for each plate being independent of the locking means for the other gates, and means to actuate said plate locking means successively to release said gate.

14. Apparatus as defined in claim 13, in which said locking means comprise a pair of lugs each pivotally mounted in said supporting member and pivotable into said gate opening to engage the undersurface of an associate gate plate when said gate plate is in a horizontal position.

15. In apparatus for handling material of the class described, the continuous gate structure comprising longitudinally extending supports, a plurality of adjacent gate plates each pivotally mounted about an axis transverse said longitudinal supports for movement from a horizontal

position closing the space between said supports to a vertically extending position opening the space between said supports, the pivotal axis of said plates being above their centers of gravity when said plates are in a vertical position, and means associated with each of said plates for locking its associated plate in its horizontal position, the locking means for each gate plate being independent of the locking means for the other gate plates, and means to actuate said plate holding means successively to release said plates and permit movement of said plates from a locked horizontal position to a vertical position.

JOSEPH E. DUNASKY.
